FLUID MOTOR

Filed Aug. 9, 1929

FIG. II.

FIG. I.

INVENTOR:

ALOYSIUS T. SPONAR,

by Arthur E. Knight
Attorney.

UNITED STATES PATENT OFFICE

ALOYSIUS T. SPONAR, OF CONSHOHOCKEN, PENNSYLVANIA, ASSIGNOR TO JOHN WOOD MANUFACTURING COMPANY, OF CONSHOHOCKEN, PENNSYLVANIA, A CORPORATION OF PENNSYLVANIA

FLUID MOTOR

Application filed August 9, 1929. Serial No. 384,632.

This invention was designed for operating a valve controlling the supply of fuel gas to a burner in a gas water heater, wherein the water is forcibly circulated by a pump, in a heating system claimed in my copending application Serial No. 384,631, filed August 9, 1929, for Letters Patent of the United States for improvement in Gas water heaters, for the purpose and effect of insuring that the water shall be in active circulation in such a system before the fuel gas valve is opened to supply such a quantity of gas as might raise the temperature of the heater to such a degree as to melt the solder joint in the water container, if the water is not thus circulated.

However, such a motor actuated valve may be utilized for other purposes and such a motor may be used to operate devices other than such a valve.

My invention includes the various novel features of construction and arrangement hereinafter more definitely specified.

In said drawings; Fig. I is a fragmentary vertical sectional view of a gas water heater including a convenient embodiment of my invention.

Fig. II is a fragmentary elevation of the left hand side of the valve and its motor, as shown in Fig. I, but on a larger scale.

In said figures; the heater structure includes the outer rectangular casing 1 having, in the far corner thereof, the cylindrical casing 2 inclosing a combustion chamber in which the burner 3 extends. Said burner is supplied with fuel gas thru the conduit 4 under control of the valve 5 which receives the gas thru the conduit 6 with which an exterior supply pipe is connected at 7.

The water is supplied to said heater from the pipe 9 which is in communication with the intake conduit 10 of the rotary pump 11 which is driven by the electric motor 12 to forcibly discharge the water thru the conduit 14 to a water jacket 15 within said casing 2; the hot water being discharged from said

heater thru the pipe 17 under control of the manually operative valve 18.

Said valve 5 is of the puppet type and is provided with the spring 19 continually tending to close it, but may be opened by its stem 21 in opposition to the stress of said spring. Said valve stem is connected by the rod 22 with the motor plunger 23 which is mounted to reciprocate thru the bearing 24 which is mounted in the frame comprising the three parallel rods 26 rigidly connected with the opposite end plates 27 and 28. Said plates 27 and 28 are respectively rigidly connected to the outer ends of the corrugated metal bellows 30 and 31 which have respective plunger plates 32 and 33 respectively rigidly connected with their inner ends. Said plunger plates 32 and 33 have respective screw threaded sockets with which said plunger 23 is adjustably connected at its opposite ends.

The effect of the construction and arrangement above described is to operatively connect said valve 5 with both of said bellows 30 and 31 so that it may be operated by fluid stresses upon both or either of them. In the embodiment shown, said bellows 30 is stressed by the pressure of water from the discharge side of said pump 11 thru the conduit 35 leading from the plate 27 of the motor to the discharge conduit 14 of said pump. Moreover, the bellows 31 is subjected to the stresses upon the water in the intake side of said pump thru the conduit 38 which extends from the motor plate 28 to the intake conduit 10 of the pump.

Therefore, it is to be understood that whenever said pump 11 is inoperative, said valve 5 is closed by its spring 19, but is opened by the aggregate stresses upon said bellows 30 and 31 incident to the operation of said pump but which are not sufficient to overcome the stress of said spring 19 until the water is in active circulation by said pump. For instance, in a commercial embodiment of the gas water heater aforesaid, said valve 5

is normally maintained shut by a spring 19 exerting a pressure of about five pounds upon said valve, and that pressure is overcome by between five and six pounds stress upon the bellows 30 plus about three pounds stress upon the bellows 31, when said pump 11 is in operation; the latter stress being imposed by the pressure of the atmosphere upon the plunger plate 33 when the water is partially exhausted from the bellows 31 by the suction of the pump.

However, it is to be understood that the respective stresses of said spring and bellows may be varied and the stresses upon said bellows be otherwise imposed. For instance, 15 said bellows 31 may be subjected to internal pressure sufficient to overcome or counter-balance the internal pressure in the bellows 30 to permit the valve 5 to be closed by its spring 19, or said spring may be omitted 20 and said valve positively opened and shut respectively by internal pressure in said bellows 30 and 31.

Therefore, I do not desire to limit myself 25 to the precise details of construction and arrangement of my invention herein set forth, as it is obvious that various modifications may be made therein without departing from the essential features of my invention, as defined in the appended claims.

I claim:

1. The combination with a valve; of a motor adapted to operate said valve independently of any fluid pressure controlled by said 35 valve including two bellows and means excluding from said bellows the fluid controlled by said valve; means rigidly operatively connecting said bellows to each other and to said valve; and means, including respective conduits connected with said bellows, adapted to 40 respectively subject them to internal fluid stresses, respectively different from and independent of the fluid stresses controlled by said valve, and sufficient to move said valve.

2. Apparatus as in claim 1; wherein the 45 bellows are in series relation and movement of either effects the movement of both, in the same direction, and extends one and contracts the other, to the same extent.

3. The combination with a valve having 50 a stem; of a motor adapted to operate said valve and including two bellows; means rigidly excluding from said bellows the fluid controlled by said valve; means 55 rigidly operatively connecting both of said bellows to said stem; and means, including respective conduits connected with said bellows, adapted to subject one of them to internal stresses tending to expand it and the 60 other of them to internal stresses tending to collapse it; whereby, said valve is subjected to the resultant of the differential internal stresses of said bellows, to move said valve, independently of the fluid controlled by said 65 valve.

4. The combination with a valve having a stem; of a motor adapted to operate said valve and including two bellows; means excluding from said bellows the fluid controlled by said valve, means operatively connecting both of said bellows to said stem; and means, including respective conduits connected with said bellows, adapted to subject one of them to internal stresses tending to expand it and the other of them to internal stresses tending to collapse it, the arrangement being such as to aggregate said stresses in one direction of movement of said valve, to open the latter.

5. The combination with a valve; of a motor adapted to operate said valve and including two bellows, in spaced relation; means excluding from said bellows the fluid controlled by said valve, a plunger between said bellows, and rigidly connected with said bellows at its respectively opposite ends; 80 a frame having opposite end plates respectively connected with the opposite outer ends of said bellows; a rod extending from said plunger to said valve; and means, including respective conduits, adapted to subject one of said bellows to internal stresses tending to expand it, and the other of them to internal stresses tending to collapse it; whereby, said valve is subjected to the resultant of the differential internal stresses of said bellows, to 85 move said valve, independently of the fluid controlled by said valve.

6. The combination with a valve; of a motor adapted to operate said valve and including two bellows, in spaced relation; a plunger between said bellows, and rigidly connected with said bellows at its respectively opposite ends; a frame having opposite end plates respectively connected with the opposite outer ends of said bellows; a rod extending from said plunger to said valve; and means, including respective conduits, adapted to subject one of said bellows to internal stresses tending to expand it, and the other of them to internal stresses tending to collapse it, independently of any fluid pressure controlled by said valve, the arrangement being such as to aggregate said stresses in one direction of movement of said valve.

7. The combination with a valve; of a 115 motor adapted to operate said valve and including two bellows, in coaxial relation; means excluding from said bellows the fluid controlled by said valve; a plunger rigidly connected with both of said bellows; and means including respective conduits connected with said bellows, adapted to separately subject them to different internal fluid stresses tending to move said valve.

8. The combination with a valve; of a 125 motor adapted to operate said valve and including two bellows, in coaxial relation; means excluding from said bellows the fluid controlled by said valve; a plunger rigidly connected with both of said bellows; and 130

means including respective conduits connected with said bellows, adapted to separately subject them to different internal fluid stresses tending to move said valve; the arrangement being such as to aggregate said fluid stresses in one direction of movement of said valve.

9. The combination with a valve; of a motor adapted to operate said valve and including two bellows, in coaxial relation; means excluding from said bellows the fluid controlled by said valve; a plunger rigidly connected with both of said bellows; and means including respective conduits connected with said bellows, adapted to separately subject them to different internal fluid stresses tending to move said valve; the arrangement being such as to aggregate said fluid stresses in one direction of movement of said valve, 20 to open the latter; and spring means adapted to close said valve when relieved from said fluid stresses.

10. The combination with a valve having a stem; of a motor adapted to operate said valve and including two sylphon bellows, in coaxial spaced relation; means excluding from said bellows the fluid controlled by said valve; a plunger between said bellows, in coaxial relation therewith, and connected with 25 said bellows at its respectively opposite ends; a frame having opposite end plates respectively rigidly connected with the opposite outer ends of said bellows; a stationary bearing plate, carried by said frame, having a stationary bearing for said plunger between said bellows; a rod extending from said plunger to said valve stem; and means including respective conduits connected with said bellows, adapted to subject one of them 30 to internal stresses tending to expand it and the other of them to internal stresses tending to collapse it.

11. The combination with a valve having a stem; of a motor adapted to operate said valve and including two sylphon bellows, in coaxial spaced relation; means excluding from said bellows the fluid controlled by said valve; a plunger between said bellows, in coaxial relation therewith, and rigidly connected with said bellows at its respectively opposite ends; a frame having opposite end plates respectively rigidly connected with the opposite outer ends of said bellows; a stationary bearing plate, carried by said frame, 45 having a stationary bearing for said plunger between said bellows; and a rod extending from said plunger to said valve stem; and means including respective conduits connected with said bellows, adapted to subject one of them to internal stresses tending to expand it and the other of them to internal stresses tending to collapse it; the arrangement being such as to aggregate said stresses in one direction of movement of said valve, to open 50 the latter.

12. The combination with a valve having a stem; of a motor adapted to operate said valve and including two bellows operatively connected with said stem; means excluding from said bellows the fluid controlled by said valve; and means, including respective conduits connected with said bellows, adapted to subject said bellows to internal fluid stresses adapted to move said valve. 70

13. The combination with a valve having a stem; of a motor adapted to operate said valve and including two bellows operatively connected with said stem; means excluding from said bellows the fluid controlled by said valve; and means, including respective conduits connected with said bellows, adapted to subject said bellows to internal fluid stresses adapted to move said valve; the arrangement being such as to aggregate said fluid stresses in one direction of movement of said valve. 75

14. A motor including two corrugated tubular bellows in coaxial relation; a plunger adapted to be moved axially by said bellows; a frame having plates respectively rigidly connected with one end of each of said bellows; and a stationary bearing plate carried by said frame, having a stationary bearing for said plunger between said bellows; and means, including respective conduits connected with said bellows, adapted to subject them to differential internal fluid stresses tending to move said plunger. 80

15. A motor including two corrugated tubular bellows in coaxial relation; a plunger adapted to be moved axially by said bellows; a frame having plates respectively rigidly connected with one end of each of said bellows; and a stationary bearing plate carried by said frame, having a stationary bearing for said plunger, between said bellows; and means, including respective conduits connected with said bellows, adapted to subject them to differential internal fluid stresses tending to move said plunger. 85

16. The combination with a valve; of a motor adapted to operate said valve, independently of any fluid controlled by said valve, and including two bellows permanently connected with said valve, and means adapted to charge said bellows with fluid and respectively subjecting them to internal stresses respectively above and below atmospheric pressure; whereby said valve is positioned by the resultant of pressure in one bellows tending to expand it and partial vacuum in the other bellows tending to collapse it. 115

17. The combination with a valve; of a motor adapted to operate said valve, independently of any fluid controlled by said valve, and including two bellows permanently connected with said valve, and means 120

adapted to charge said bellows with fluid and respectively subjecting them to internal stresses respectively above and below atmospheric pressure; whereby said valve is 5 opened by the resultant of pressure in one bellows tending to expand it and partial vacuum in the other bellows tending to collapse it.

In testimony whereof, I have hereunto 10 signed my name at Conshohocken, Pennsylvania, this twenty-second day of July, 1929.

ALOYSIUS T. SPÖNAR.
